DESIGN FOR A COMBINATION TEA KETTLE, COFFEE MAKER, AND DOUBLE BOILER OR ARTICLE OF A SIMILAR NATURE

Walter B. Moore, West Lafayette, Ohio

Application July 16, 1945, Serial No. 120,735

Term of patent 14 years

(Cl. D44—26)

To all whom it may concern:

Be it known that I, Walter B. Moore, a citizen of the United States of America and a resident of West Lafayette, in the county of Coshocton and State of Ohio, have invented a new, original, and ornamental Design for a Combination Tea Kettle, Coffee Maker and Double Boiler or Article of Similar Nature, of which the following is a specification, reference being had to the accompanying drawing, forming a part hereof.

or article of similar nature, showing my new design.

I claim:

The ornamental design for a combination tea kettle, coffee maker and double boiler or article of similar nature, substantially as shown.

WALTER B. MOORE.
